Inventor:

William W. Ensign,
by *Charles Peck*,
his Attorney.

UNITED STATES PATENT OFFICE.

WILLIAM W. ENSIGN, OF CINCINNATI, OHIO, ASSIGNOR TO THE BENNETT & PECK HEATING AND VENTILATING COMPANY, OF OHIO.

DESIGN FOR A RACK.

SPECIFICATION forming part of Design No. 23,200, dated April 17, 1894.

Application filed March 12, 1894. Serial No. 503,365. Term of patent 7 years.

To all whom it may concern:

Be it known that I, WILLIAM W. ENSIGN, a citizen of the United States, residing at Cincinnati, in the county of Hamilton and State of Ohio, have invented and produced a new and original Design for Racks, of which the following is a specification, reference being had to the accompanying drawing, forming part thereof.

• The figure is a perspective of one section of a rack embodying my invention; this view being deemed sufficient to fully illustrate my design.

The leading feature of my design consists in the brackets of the rack. This, as shown in the drawing, consists of a straight vertical attaching piece A from which projects upward at the upper end, at an angle of about forty-five degrees a straight perforated piece B, the perforations being represented by *a* in a

sunken panel in the side of the piece B. The pieces A and B are connected at or about their middle, on the under side, by a scroll C with inturned volutes *b* at its ends. The upper end of each piece B, has a rearwardly 25 turned volute or knob *c* and the lower ends of the pieces A are ornamented by beads *d, e*, the latter terminating in a point or sharp edge. The brackets are secured at equal intervals to a back board D and are connected by rods 30 *E*, inserted through the perforations *a*, the whole forming a harmonious design for a rack such as I have described.

What I claim is—

The design for a rack, substantially as 35 shown and described.

WILLIAM W. ENSIGN.
